Fig. 4

Fig. 5

Fig. 6

FIG. 1 is an elevational front view of a picture telephone showing my design;

FIG. 2 is an elevational side view of FIG. 1;

FIG. 3 is an elevational rear view of FIG. 1;

FIG. 4 is a top plan view of FIG. 1;

FIG. 5 is a perspective view of the picture telephone according to my design; and

FIG. 6 is a perspective view similar to FIG. 5 in position ready for use.

I claim:

The ornamental design for a picture telephone, as shown.
